(57) **CLAIM**

The ornamental design for a toy cart, as shown and described.

DESCRIPTIONFIG. 1 is a top perspective view of a toy cart showing the new design;
FIG. 2 is a front side elevational view of the toy cart of FIG. 1;

FIG. 3 is a rear side elevational view of the toy cart of FIG. 1;

FIG. 4 is a right side elevational view of the toy cart of FIG. 1;

FIG. 5 is a left side elevational view of the toy cart of FIG. 1;

FIG. 6 is a top plan view of the toy cart of FIG. 1; and,

FIG. 7 is a bottom plan view of the toy cart of FIG. 1.

The broken lines and unshaded areas adjacent the broken lines form no part of the claimed design.

1 Claim, 7 Drawing Sheets---
